UNITED STATES PATENT OFFICE.

WARREN H. CONOVER, OF FREEHOLD, NEW JERSEY, ASSIGNOR OF ONE-HALF TO JAMES PARKER, OF JERSEY CITY, NEW JERSEY.

COMBINED RANGE, &c., AND HEATING APPARATUS.

No. 813,950.

Specification of Letters Patent.

Patented Feb. 27, 1906.

Application filed May 17, 1902. Serial No. 107,830.

To all whom it may concern:

Be it known that I, WARREN H. CONOVER, a citizen of the United States, residing at Freehold, in the county of Monmouth and State of New Jersey, have invented certain new and useful Improvements in a Combined Range, Stove, Furnace, &c., and Heating Apparatus; and I do hereby declare the following to be a full, clear, and exact description of the invention, such as will enable others skilled in the art to which it appertains to make and use the same.

My invention relates to improvements in hot-water heating systems.

It is the object of my invention to provide means wherein the water may be thoroughly heated without interfering with the circulation of the water through the heating system.

Another object of my invention is to provide a water-heating apparatus which may be associated with ranges and cooking-stoves to thereby utilize such stoves for heating houses and apartments.

The accompanying drawings illustrate an embodiment of my invention.

It will of course be understood that the apparatus illustrated in the drawings may be changed in many ways without departing from my invention, and, furthermore, that the invention may be embodied in various different forms.

The views in said drawings are as follows: Figure 1 is a front elevation of a range provided with my hot-water heating apparatus. Fig. 2 is a longitudinal sectional view on the line *x x* of Fig. 1. Fig. 3 is a similar sectional view on the line *y y* of Fig. 2. Fig. 4 is a cross-sectional view on the line *z z* of Fig. 2.

The range or stove 1 is provided with a fire-box 2, having a grate 3. An upper compartment 4 and a lower compartment 5 are arranged at the rear of the fire-box. The return-pipe 5^a of a hot-water heating system is connected to the lower rear compartment 5. An upper compartment 6 and a lower compartment 7 form one side wall of the fire-box, and an upper compartment 6^a and a lower compartment 7^a form the other side wall thereof. The lower side compartments 7 and 7^a communicate with the lower compartment 5 by means of the short pipes 5^b, and the upper side compartments 6 and 6^a communicate with the upper compartment 4 by means of the short pipes 4^a. The side

compartments 6 and 7 communicate with each other at the forward ends thereof by a passage 8, and the side compartments 6^a and 7^a also communicate with each other, at the forward ends thereof, by a passage 8^a.

A heating-chamber 9 is preferably mounted upon the stove, and it communicates at its bottom with the fire-box and at its top with the chimney. Within this heating-chamber is arranged a series of water-heating compartments 10, arranged one above the other. Each compartment is arranged upon the opposite side of the heating-chamber from its adjacent compartments, so as to provide a sinuous or tortuous passage 11 through the heating-chamber 9. Each compartment is connected with its adjacent compartments by a single pipe or similar means 12, and the pipes connecting the several compartments are arranged substantially in alignment. A straight and single passage is thus provided through the heating-chamber.

The lower water-heating compartment 10 is connected to the upper rear compartment 4, and the upper water-heating compartment 10 is connected to the delivery-pipe 13 of the hot-water heating system. Upon one side of the heating-chamber 9 is arranged a flue 14, which communicates with the fire-box at the bottom and with the chimney at its top. The flue 14 may be provided with a sliding damper adapted to close the same. A damper 15^a may be provided to close the passage between the chimney and either the heating-chamber 9 or the flue 14.

The front of the heating-chamber 9 is preferably provided with doors 16, through which access may be had to the water-heating compartments 10.

A boiler 17, to which hot water is furnished by means of a water-heating receptacle 18, may be provided to supply hot water for general purposes. The receptacle 18 may be arranged at the front of the fire-box, so as to be heated by the fire, and it is connected to the boiler in the usual manner.

The cooled water returning from the heating system through the return-pipe 5^a enters the lower rear compartment 5 and passes through the lower side compartments 7 and 7^a, passages 8 and 8^a, upper side compartments 6 and 6^a, upper rear compartment 4, pipes 12, and water-heating compartments 10 to the delivery-pipe of the water-heating

system. The hot air from the fire-box passes through the heating-chamber 9, and as it passes therethrough it passes under and over the water-heating compartments 10 and 5 thoroughly heats the same. Inasmuch as the hot air is somewhat retarded in its progress through the heating-chamber, it remains within said chamber until the hot-water heating compartments 10 absorb considerable heat therefrom.

When the system is in operation, a continuous current of water will flow through the passage extending through the water-heating compartments 10 and the pipes 12. The 15 cool water in this current will pass into the water-heating compartments to be reheated and hot water will enter the current from said compartments. As the passage extending through the compartments 10 and the 20 pipes 12 is substantially straight, the movement of the current therethrough will not be retarded, and therefore the circulation of the hot air throughout the heating system will not be impeded in the heating apparatus. Inasmuch as merely a single passage extends 25 through the heating-compartments 10 and pipes 12, counter-currents which would interfere with the movement of the main current will be avoided.

30 It will of course be understood that the apparatus which is shown in the drawings and described herein may be changed in many ways and still be within the purview of the claims appended hereto.

35 Having thus described my invention, what I claim, and desire to secure by Letters Patent, is—

1. In a water-heating appliance for hot-water heating systems, in combination, a heating-chamber, a plurality of water-heating compartments arranged one above the other within said heating-chamber, each compartment being arranged on the opposite side of said heating-chamber from the adjacent 45 compartment to provide a sinuous passage through said chamber between said compartments, and a single pipe connecting each compartment with the adjacent compartment, the pipes connecting the several compartments being arranged substantially in alinement, whereby a straight and single passage is provided through said heating-compartments.

2. In a water-heating appliance for hot-water heating systems, in combination, a fire-box, a heating-chamber communicating with said fire-box, a water-heating device having a plurality of water-heating compartments arranged one above the other within said heating-chamber, each compartment being arranged on the opposite side of said heating-chamber from the adjacent compartment to provide a sinuous passage through said heating-chamber between said compartments, a 60 return-pipe of a hot-water heating system

communicating with the bottom compartment, a delivery-pipe of a hot-water heating system communicating with the upper compartment, and a single pipe connecting each compartment with the adjacent compartment, the pipes connecting the several compartments being arranged substantially in alinement, whereby a straight and single passage is provided through said compartments.

3. The combination with a stove, of a water-heating chamber arranged at the rear of said stove and communicating with the fire-box thereof, said heating-chamber being in communication with the chimney of the stove, a plurality of water-heating compartments arranged one above the other within said chamber, each compartment being arranged on the opposite side of said chamber from the adjacent compartment to provide a sinuous passage through said chamber between said compartments, a single pipe connecting each compartment to the adjacent compartment, the pipes connecting the several compartments being arranged substantially in alinement, whereby a straight and single passage is provided through said heating-compartments, a return-pipe communicating with the bottom compartment, and a delivery-pipe communicating with the upper compartment.

4. The combination with a stove, of a water-receptacle arranged around the fire-box thereof, a return-pipe connected to said receptacle, a heating-chamber arranged at the rear of said stove and communicating with said fire-box and also the chimney of the stove, a plurality of water-heating compartments arranged one above the other within said heating-chamber, each compartment being arranged on the opposite side of said heating-chamber from the adjacent compartment to provide a sinuous passage through said chamber between said compartments, a single pipe connecting each compartment to the adjacent compartment, the pipes connecting the several compartments being arranged substantially in alinement, whereby a straight and single passage is provided through said heating-compartments, and a delivery-pipe connected to the upper compartment, the lower compartment being connected to said receptacle.

5. The combination of a range, stove, furnace, &c., and a water-heating apparatus consisting of a chamber having a lower section provided with an inlet and an upper section provided with an outlet, said sections communicating with each other at the end opposite the outlet and inlet and communicating with corresponding upper and lower sections of a second heating-chamber at the opposite side of the fire-box, to provide a tortuous passage therethrough, substantially as set forth.

6. The combination, with a range, stove,

furnace, &c., of a water-heating apparatus having, at opposite sides of the fire-box of said stove, &c., lateral subdivided chambers, each of the thus formed upper and lower 5 compartments of said chambers communicating at one end with each other, and a second compartment or subdivided chamber arranged at the back of said fire-box with its compartments communicating with the upper and lower compartments of said lateral chambers, at the opposite ends of the last named, and having an outlet and an inlet passage, respectively, substantially as set forth.

15 7. The combination of a stove, range, furnace, &c., a water-heating apparatus having opposite chambers provided with upper and

lower sections communicating with each other at one end and opening at their opposite ends into common corresponding upper 20 and lower chambers or compartments, separated one from the other, said lower chamber having a delivery-opening and said upper chamber communicating with a boiler, comprising a series of sections or compartments 25 connected by means which form a lining passages therethrough, arranged within said heating-chambers, substantially as set forth.

In testimony whereof I affix my signature in presence of two witnesses.
